UNITED STATES PATENT OFFICE.

EUGÈNE BREUIL, OF LIMOGES, FRANCE, ASSIGNOR TO FRANCIS H. BAWO
AND CHARLES T. DOTTER, OF BROOKLYN, NEW YORK.

DESIGN FOR A HANDLE FOR DISHES.

SPECIFICATION forming part of Design No. 18,006, dated January 10, 1888.

Application filed November 5, 1887. Serial No. 254,444. Term of patent 7 years.

To all whom it may concern:

Be it known that I, EUGÈNE BREUIL, of Limoges, France, have originated and produced a Design for Table-Ware, of which the following is a specification.

My design consists in a handle or hand-piece of novel form, consisting of two band-like portions terminating in representations of leaves which interlock, intertwine, or embrace one another.

In the accompanying drawings, Figure 1 is a plan of a covered dish embodying my design. Fig. 2 is a side view of such dish. Fig. 3 is an end view of such dish.

Similar letters of reference designate corresponding parts in all the figures.

The dish shown in Figs. 1, 2, and 3 is provided at each end of the body with a handle or hand-piece, and the cover of the dish is provided with a similar handle or hand-piece. Each handle or hand-piece consists of two band-like portions, $b' b^2$, which have the appearance of extending from the dish or the cover and approaching and meeting each other. The meeting ends of these two band-like portions are shaped to represent a leaf, which, for

instance, is a grape-leaf, and the two leaves $b^3 b^4$ of the band-like portions $b' b^2$ interlock, intertwine, and embrace each other. The band-like portions are also represented as being provided with ribs along the edges $b^5 b^6$ and as being embellished with button-like ornaments $b^7 b^8$ between the ribs.

In the dish shown in Figs. 1, 2, and 3 it will also be observed that the band-like portions $b' b^2$ at the point of union with the dish extend for a distance parallel with the dish, then diverge from each other, and then approach and meet.

What I claim as new, and desire to secure by Letters Patent, is—

In a design for a dish, a handle for the same consisting of two band-like portions extending toward each other and having terminal meeting portions representing interlocked, intertwined, or embracing leaves, substantially as shown and described.

EUGÈNE BREUIL.
